UNITED STATES PATENT OFFICE.

JAMES M. DAVIES, OF GRAND RAPIDS, MICHIGAN, ASSIGNOR OF ONE-HALF
TO CHARLES H. KAHLER, OF SAME PLACE.

SKIRT-SUPPORTER.

SPECIFICATION forming part of Letters Patent No. 555,682, dated March 3, 1896.

Application filed July 16, 1895. Serial No. 556,189. (No model.)

To all whom it may concern:

Be it known that I, JAMES M. DAVIES, a citizen of the United States, residing at Grand Rapids, in the county of Kent and State of Michigan, have invented certain new and useful Improvements in Skirt-Supports; and I do hereby declare the following to be a full, clear, and exact description of the invention, such as will enable others skilled in the art to which it appertains to make and use the same.

My invention relates to improvements in skirt-supports, and more particularly to supports for lady bicyclists' skirts; and its object is to provide the same with certain new and useful features hereinafter more fully described and particularly pointed out in the claims, reference being had to the accompanying drawings, in which—

Figure 1 shows the position of the skirt when my device is used. Fig. 2 is a detail showing position of my device when in use; Fig. 3, an enlarged detail to show construction, and Fig. 4 a detail of the adjustable fastening.

Like letters refer to like parts in all of the figures.

A is an ordinary belt having a buckle D, to which is secured a ring B to receive a loop in one end of the cord C, said cord having a similar loop at its other end adapted to engage said belt at the side opposite said buckle. To the ends of said cord are attached the plates E at E', and after forming said loops said cord is passed through the openings E'' in said plates and then returned through the openings E''', thus forming a fastening which will not slip, but may be adjusted to lengthen or shorten said cord, as desired. Said cord C being attached at each end to said belt A, its intermediate portion hangs downward, as shown in Fig. 2, forming a loop, and to the lowest point of said loop are attached the clasps F, adapted to engage the lower edge of the dress-skirt at points directly at the front and rear. To said cord C, near said clasps, are attached the ends of the cords G; and to the other ends of said cords are attached the clasps H, which clasps, when a portion of the skirt directly at each side is

brought up and the lower edge drawn tightly 50 about the leg, engage said edge and hold the same in place.

By fastening that part of the skirt which is directly at the side about the leg I bring the fullness of said skirt between the legs, 55 thus giving room to step, and by bringing the bottom of the same toward the knee and fastening it there said skirt will fall over said bottom in folds, where it is fastened about the leg, and have the appearance of bloomers. 60

The cord C supports the skirt between the legs and may be adjusted by moving the fastenings E to any desired height, while clasps F on said cord hold the front and rear of the bottom between the legs and prevent the said 65 fullness of said skirt from slipping from one side to the other of said cord. By this arrangement of parts I provide a device whereby an ordinary dress-skirt may be quickly and easily arranged to appear like the ordinary bloomers worn by lady bicyclists and to have all the conveniences thereof. 70

I do not wish to confine myself to any particular form of belt, cord, or clasp. A chain may be used instead of a cord and any convenient form of clasp or fastening may be used; but 75

What I claim is—

1. A skirt-supporter for the purpose specified, embodying a waistband, a main loop depending therefrom and arranged to support the skirt between the wearer's limbs, fasteners on said loop for engaging the front and rear of the bottom of the skirt, and cords extending from said loop and provided at their 85 free ends with fasteners for engaging the edge of the skirt.

2. A skirt-supporter for the purpose stated, consisting of a waistband, a main loop depending from the center thereof and serving 90 to support the skirt between the wearer's limbs, a plate to which one end of said loop is secured, said plate serving to lengthen and shorten the loop and having a plurality of openings through which the latter extends, 95 fasteners projecting from the lower end of the loop to engage the front and rear of the bottom of the skirt, and cords, each secured

at one end to the bottom of said loop and having a fastener at its free end, for the purpose specified.

3. The herein-described skirt-supporter, consisting of a waist-belt, a loop having its ends secured to the front and back of said belt, said loop supporting the skirt in divided condition between the wearer's limbs, and fasteners extending from the loop for con-

fining the halves of the skirt around the respective limbs of the wearer, substantially as described and for the purpose specified. 10

In testimony whereof I affix my signature in presence of two witnesses.

JAMES M. DAVIES.
